ATTORNEY

UNITED STATES PATENT OFFICE.

DONALD C. McMILLAN, OF BROOKLYN, NEW YORK.

NONTWISTING, NONTOPPLING TACKLE BLOCK FOR BOAT DAVITS.

Application filed March 25, 1922. Serial No. 546,576.

To all whom it may concern:

Be it known that I, DONALD C. McMILLAN, a citizen of the United States, and resident of the borough of Brooklyn, county of 5 Kings, city and State of New York, have invented new and useful Improvements in Nontwisting, Nontoppling Tackle Blocks for Boat Davits, of which the following is the specification.

10 The device, the subject of this invention is a tackle block intended for all general service, but so designed as to operate with a higher degree of efficiency than the ordinary block.

15 Because of the shape of my blocks, it will appear quite obvious that they may be worked closely together. This is important in the handling of nested life boats, where but little drift is usually allowed, the purpose being to retain the davits or stanchions 20 at a minimum height.

25 Another important feature to be found in my block is the provisions upon the lower block which prevent the toppling, twisting or fouling of the block.

Another important object is to so construct the blocks that a maximum strength may be obtained from a minimum size and weight.

30 Other objects and features and the details of construction will be fully set forth as the specification progresses and the accompanying drawing should be referred to for a complete understanding of the specification 35 which follows:

In the drawing:

Fig. 1, is a perspective view of a boat and davits.

Fig. 2, is a central, vertical section 40 through the upper block, certain parts being in elevation.

Fig. 3, is a central, vertical section of the lower block, certain parts being in elevation.

Fig. 4 is a perspective view of a pair of 45 blocks in operative position.

Fig. 5, is a perspective view of the guides.

Similar reference numerals indicate like parts in all the figures where they appear.

As it is customary for tackle blocks to 50 act in pairs, I have shown and will describe a pair of blocks constructed according to my invention.

The upper block is provided with a shell or casing 10, which may be of wood or any 55 other suitable material, though in the block

shown, the wooden construction is preferred. This casing or shell is formed of a suitable number of parts to provide mortises or passages wherein the sheaves are arranged, and in the construction I show three such mortises, indicated at 11, 12 and 13, wherein are arranged the sheaves 14, 15 and 16.

These sheaves are provided with suitable bearings, such as, roller bearings as shown at 17 in Fig. 3 or bronze self lubricating 65 bearings or bearings of any other preferred type and are rotatably supported upon a common pin or shaft 18, which extends through the casing.

At one end of the pin 18, I provide an 70 eye 19, as shown and at the other end, a nut 20 to retain the pin in place.

I call particular attention to the straps shown in detail in Fig. 2. These straps extend quite through the casing 10 and are of 75 a large U-shape, the arms of the strap 21 extending outward, are provided with perforations through which the pin 18 passes. The arms of the strap 22 also receive the pin 18. Both of the straps are provided with 80 loops or return bends, through which may be passed the pin 23 of the shackle 24 and it will be noted from a study of this construction that the casing 10 carries no load, its only functions are to incase the sheaves, 85 to act as a guide for the falls and to guard the sheaves and falls against injury or entanglement.

Pins as shown by the dotted lines 25 and 90 26 secure the several parts of the casing together and to the straps or U-shape members 21 and 22.

As previously stated, it is my desire that the blocks operate in close proximity to each other and to make this possible it will be noted that the casing for each block has a flattened portion and in the upper block, while the upper part of the casing adjacent the shackle 24 is rounded or shaped in the customary manner, the block is actually triangular in end elevation, the base of the triangle being next adjacent to the lower block and the straps and shackle being arranged at the apex of the triangle for the purpose of symmetry and to prevent the block catching upon abutting surfaces, the points of contact of adjacent sides of the triangle are rounded.

To further reduce the necessary separation between blocks of a pair, the becket or 110

secured end 27 of the falls 28 is made fast to the eye 19, which it will be noted is at the side of the block.

The second block of the pair shown in section in Fig. 3, is the travelling or lower block and in shape and size corresponds to the upper block previously described.

This block may have any number of sheaves, but I have shown three to accommodate the tackle arrangement shown which is the tackle usually employed with life boat davits. These sheaves 29, 30 and 31 are rotatable upon a pin 32, which is provided with an eye 33 and a nut 34 for retaining 15 the pin in position.

The straps 36 and 37 are formed integral with a plate member 38, wherein is secured a swivel-eye 39, to which a boat releasing device may be secured.

20 In the eye 35 of the pin 32, I may arrange a shackle 40, or thimble for a purpose that shall appear later.

I call particular attention to the guide plates 41 and 42 arranged one at each side 25 of the block and having extended portions fitting into the mortises of the block. These plates guide the falls and prevent capsizing or toppling of the block.

When these blocks are employed as a part 30 of the davit equipment, as shown, a cable or spar 43 may be secured to oppositely arranged eyes 19, 35 or shackles 40 and will further assist in retaining the blocks against twisting during operation.

35 It is obvious that any other fitting desired may be substituted where eyes or shackles are shown, that blocks may be constructed

with any number of sheaves and that other modifications may be made within the scope of the appended claims without departing 40 from the principle or sacrificing the advantages of the invention.

I prefer the whole as shown and described, however, and desire to adhere to shape and 45 general construction as the best means for accomplishing the purposes sought.

Having carefully and fully described my invention what I claim is:—

1. A pair of tackle blocks adapted to operate in close proximity, said tackle blocks being of approximate triangular shape with the bases of the triangles next adjacent to each other, an eye at one side of one said block for the reception of the becket and non-tilting means upon the other said block and adjacent to the base of the triangle said means comprising guides projecting into the mortises of the block.

2. A pair of tackle blocks adapted to operate closely adjacent, both said blocks being approximately triangular in elevation, a plurality of straps passing through one said block, a pin passing through said straps supporting the sheaves therein and an eye on said pin for the reception of the becket, a plurality of straps passing through the other said block, a pin passing through said straps to support the sheaves in said block and an eye on said pin to receive a cable to prevent the twisting of said block.

Signed at the city, county and State of New York, this 15th day of March, 1922.

DONALD C. McMILLAN.
